GOLF BALL RETRIEVING MACHINE

Leslie Woodall, Windsor, Ontario, Canada

Application August 19, 1953, Serial No. 375,254

3 Claims. (Cl. 214—356)

This invention relates to golf driving range equipment and, in particular, to golf ball retrieving machines.

Golf driving ranges, where golfers practice their driving strokes, in the course of such practice receive hundreds of golf balls which are driven out into the grass of the range to widely scattered locations. From time to time it becomes necessary to pick up these golf balls and return them to the tees for reuse. The problem of picking up this enormous number of widely-scattered golf balls is complicated by the fact that there are two sizes of golf balls still in use upon such ranges—the older and now superseded 1.62 golf ball and the newer and larger 1.68 golf ball which has replaced it in competition. This problem is still further complicated by the fact that some balls become knocked out of round. It is expensive for operators of such ranges to replace all of the older and smaller golf balls with the newer and larger ones, especially since such balls are subjected to such rough treatment that it is costly enough even when using balls of both sizes.

Golf ball retrieving machines hitherto devised have frequently been the cause of damaging many of the golf balls while they were being picked up, and such prior machines have been incapable of satisfactorily picking up both sizes of balls or balls which are out of round. Certain prior machines, moreover, have caused damage to the turf when turning corners while others have suffered from inflexibility and inadaptability to both small and large driving ranges.

One object of the present invention is to provide a golf ball retrieving machine which is adapted to rapidly and efficiently retrieve balls of both sizes currently in use, even when both sizes are distributed indiscriminately over the range.

Another object is to provide a golf ball retrieving machine wherein the balls are retrieved by resiliently mounted discs which not only pick up both sizes of ball and balls which are out of round, but also by their resilient mounting firmly grip the balls as well as yielding sufficiently to prevent damage to the ball if a ball is encountered accidentally directly under one of the discs.

Another object is to provide a golf ball retrieving machine which turns corners easily without digging up the turf and which is also easily backed.

Another object is to provide a golf ball retrieving machine which is assembled in independent units connected to one another so that a small golf driving range may use only one or two units, whereas a large one can assemble as many as five units side by side in one machine, the different units being linked together by parallel links which enable them to rise and fall independently so as to adjust themselves to irregularities in the terrain.

Other objects and advantages of the invention will become apparent during the course of the following description of the accompanying drawings, wherein:

Figure 1 is a top plan view of one of the self-contained units of a golf ball retrieving machine, according to one

2

form of the present invention, with a removable golf ball receiving container indicated in dotted lines;

Figure 2 is a side elevation of the golf ball retrieving unit of Figure 1, with the removable golf ball receiving container similarly shown in dotted lines;

Figure 3 is an enlarged fragmentary vertical section through a pair of the golf ball retrieving discs and the ball guide between them, taken along the line 3—3 in Figure 1; and

Figure 4 is a top plan view of a complete machine consisting of five interlinked units of the type shown in Figures 1 and 2.

Referring to the drawings in detail, Figure 4 shows a golf ball retrieving machine, generally designated 10, as consisting of a plurality of identical but independent golf ball retrieving units, generally designated 12. Five such units are shown for purposes of illustration, but it will be self-evident and distinctly understood that a greater or lesser number may be used depending upon the size of the range and the volume of golf balls requiring retrieving. Moreover, the machine may be started with one or two units, and other units 12 may be added from time to time as the range increases in size or use or becomes financially better able to afford a larger machine. The central unit 12 is connected by a main draw bar 14 to a tractor or other towing machine, the draw bar 14 having a hook or right-angle bend 16 at its rearward end and a coupling eye 18 at its forward end.

Also welded or otherwise secured to the forward end 30 of the main draw bar 14 is a coupling plate 20 having spaced multiple holes 22 therein, these holes being engaged by the forward bent ends 24 of secondary draw bars 26, the rearward bent ends 28 of which are connected to the outlying units 12 in a similar manner to 35 the central or main draw bar 14, as described below in connection with the description of the individual units 12. The individual units 12 are interconnected laterally by floating links 30 secured by pivot bolts or pivot pins 32 at their opposite ends to the respective adjacent units, 40 which are separated laterally a slight distance from one another to enable relative rise and fall of one unit relatively to its neighboring unit or units without flashing or conflicting with one another.

Each machine unit 12 consists of a rectangular main frame 34 composed of front and rear channel members 36 and 38 interconnected by side channel members 40. Intermediate their opposite ends, the side channel members 40 are interconnected by an intermediate cross channel member 42. The forward and intermediate cross channel members 36 and 42 are interconnected by a central longitudinal channel member 44 whereas the intermediate and rear cross channel members 42 and 38 are similarly interconnected by slightly spaced parallel channel members 46. Similarly, the outer ends of the same cross channel members 42 and 38 are interconnected adjacent the channel members 40 by supplemental channel members 48. These various frame members 36 to 48 are preferably secured to one another by welding in order to form the main frame 34.

Bolted or otherwise secured to the channel members 46 and 48 and depending therefrom are two pairs of aligned journal bearings or shaft hangers 50 in which two coaxial but longitudinally spaced shafts 52 are rotatably mounted. Secured at intervals along each shaft unit 52 are axially spaced sets or pairs, collectively designated 54, of ball pickup wheels 56 and 58 respectively. The wheels 56 and 58 are similar in construction to one another but face in opposite directions (Figure 3) so that a single description and a single set of reference numerals will suffice for both.

Each ball pickup wheel 56 or 58 of the pair or set 54 consists of a central flanged hub 60 bored as at 62 to

receive the shaft 52 and drilled and threaded transversely to receive a set screw 64 by which the hub 60 is locked at a desired location along the shaft 52. The annular flange 66 of the hub 60 is provided with paraxial holes 68 spaced circumferentially around the flange 66 and receiving bolts 70 which pass through similarly-spaced holes 72 in the inner periphery of a resilient disc or ring 74 and thence through similarly spaced holes 76 in a retaining ring 78 mounted on the inner side of the assembly 56 or 58. The resilient disc 74 is seated in an annular depression or rabbet 80 in the hub 60 adjacent the flange 66 and secured therein by the bolts 70.

The outer periphery of each resilient disc 74 is provided with circumferentially-spaced holes 82 aligned with similarly spaced holes 84 in the inner periphery of an annular outer ball pickup disc 86 having an outwardly curved or flared outer peripheral rim 88. The resilient inner rings or discs 74 and the annular outer discs 86 are held in assembly with one another by bolts or rivets 90 passing through the aligned holes 82 and 84. The resilient disc or ring 74 is preferably of flexible or elastic material such as natural or synthetic rubber containing a plurality of spaced layers of corded fabric, similar to the material from which rubber conveyor belts are made. The outer discs 86 are conveniently made of sheet metal.

Secured as by welding to the intermediate cross channel members 42 at intervals thereacross are the forward ends 92 of ball ejector or interceptor fingers or bars 94, each of these bars 94 extending rearwardly in a chordal direction between each pair of ball pickup wheels 56 and 58, and having its rearward end 96 terminating approximately over the shaft 52 or slightly rearwardly thereof. The fingers or bars 94 are located slightly above the junctions of the resilient discs 74 and the outer annular discs 86 (Figures 2 and 3) so that they intercept all golf balls 98 caught and held between the outer discs 86, as described below in connection with the operation of the invention.

Secured at its upper end to the cross channel member 42 between each set or pair 54 of ball pickup wheels 56 and 58, is a vertical angle member or arm 100 to the lower end of which an approximately V-shaped ball deflector 102 is secured, likewise preferably by welding. The ball deflector 102 consists of angled, forward portions 104 diverging relatively to one another from their forward ends at the arm 100 and rearward parallel portions 106 extending rearwardly from the rearward ends of the portions 104 into close proximity to the lower rims 88 of the ball pickup wheels 56 and 58 (Figures 1 and 2). The outer end portions 106 have downwardly-inclined upper edges 108 in order to bring them close to the disc peripheries 88 (Figure 2). Cooperating with the V-shaped ball deflectors 102 at the outer ends of the shafts 52 are half ball deflectors 110. These, as their names signify, consist of vertical angle arms or bars 112 secured at their upper ends to the side channel members 40 adjacent the outer ends of the intermediate cross channel member 42.

Secured to the lower ends of the arms 112 are deflector bars 114 having inwardly-inclined forward portions 116 terminating in rearward end portions 118 similar to the end portions 106 and having downwardly-inclined upper edges 120 similarly disposed, relatively to its respective wheel 56 or 58. Secured as by welding at their upper ends to the forward and intermediate cross channel members 36 and 42 are approximately U-shaped ball container rests 122 disposed at intervals along the members 36 and 42. These supports 122, in cooperation with the adjacent portions of the members 36, 40, 42 and 44 provide spaces 123 for receiving rectangular baskets or ball containers or receptacles 124 shown in dotted lines in the lower right-hand corner of Figure 1 and in the central portion of Figure 2. Each of the baskets 124 is provided at its upper forward edge with a guard or deflector portion 126 extending thereacross approximately halfway.

over the top of the basket and inclined upwardly and rearwardly (Figure 2) to prevent balls 98 from being thrown forwardly entirely over the basket 124. The baskets 124 may be made of metal mesh material and are removably mounted in the spaces 123.

Welded or otherwise secured to the central portion of the forward cross channel member 36 and extending forwardly therefrom is a horizontal tow plate 128 having a hole 130 in the forward end thereof adapted to receive the rearward bent end 16 or 28 of the main or secondary draw bar 14 or 26, as the case may be. Bolted or otherwise secured to the underside of the tow plate 128 is the base 132 of a swivel caster, generally designated 134, and including a pivot pin 136 passing through the base 132 and the bridge portion 138 of a fork 140 carrying an axle 142 for a caster wheel 144 equipped with a rubber tire 146. The swivel caster 134 turns to and fro around its pivot pin 136 as the machine 10 changes course or turns corners.

In the operation of the invention, let it be assumed that five units 12 have been linked together side by side by the floating links 30, and pivot bolts 32 (Figure 4), and that their respective tow plates 128 have been connected to the coupling plate 20 either by the main draw bar 14 or the secondary draw bar 26. Let it finally be assumed that ball receptacles or baskets 124 have been placed in the spaces 123 intended to receive them, and that a tractor or other towing vehicle has been coupled to the hole 18 in the forward end of the main draw bar 14. The operator then tows the machine 10 over the golf driving range, proceeding back and forth until the entire range has been covered.

As each unit 12 of the machine 10 moves along over the ground, any golf balls lying in its path are deflected by the ball deflectors 102 or 110 into the spaces between the pairs or sets 54 of ball pickup discs 56 and 58. These are placed apart from one another a distance slightly smaller than the minimum diameter of the golf balls they are intended to pick up, and as they roll over a golf ball 35 it becomes wedged into the space between the opposing outer discs 86 after being possibly deflected by the flared or rounded peripheries 88 thereof (Figure 3). The balls 98 thus wedged between the discs 86 are held firmly by the resilience of the inner elastic discs or rings 72 and pass 40 around as indicated by Figure 2 until they collide with the fingers or bars 94, whereupon each ball 98 rolls along the top of its intercepting ring 94 and drops into the basket or ball receptacle 124. Since the outer discs 86 of each set 54 of disc assemblies 56 and 58 are resiliently mounted, 45 small diameter balls, large diameter balls or deformed balls are readily intercepted, picked up and deposited in the baskets 124. When the baskets 124 become filled or the operator reaches the end of his path of travel over the driving range, the balls are removed from the baskets 124 and the machine is ready for another trip over the driving range.

The construction whereby each unit 12 carries two shafts 52 assists the unit in turning corners without digging up the grass. The construction of the machine enables it to be backed readily, even though it consists of five units, each unit 12 of which, for example, may be five feet wide. As the machine 10 moves over the undulating terrain of the driving range, the various units 12 rise and fall relatively to one another by reason of their interconnection by the parallel floating links 30. In this manner, the machine covers the irregular surface of the range and picks up all of the golf balls from the grass or ground thereof.

Thus there has been provided a golf-ball retrieving machine by which the balls are picked up by smooth steel discs which provide less friction and therefore less tendency to remove the paint from the ball. After years of use, these steel discs remain substantially the same and wear is negligible, any roughness caused by running over stones being limited to the outer edge, away from the

balls. In the event of an accident, such as a heavy truck running into a unit, that unit can be disconnected and the range operator can still use the undamaged units as before.

What I claim is:

1. A golf ball retrieving machine comprising a frame adapted to be moved over the ground, a shaft mounted transversely on said frame, a plurality of pairs of ball pick-up wheels mounted on said shaft at laterally-spaced locations thereacross, each wheel having a hub mounted in an axially-fixed location on said shaft and a centrally-apertured peripheral disc tiltably mounted on said hub in radially-spaced encircling relationship thereto, and resilient means disposed between said hub and said disc and yieldingly connecting said disc to said hub, said resilient means normally urging said disc into a plane perpendicular to said shaft, the hubs of each said pair of wheels being mounted on said shaft at intervals normally spacing the peripheries of said discs apart from one another by a distance slightly less than the diameter of the smallest ball to be picked up, a ball receptacle mounted on said frame, and a ball ejector disposed in the path of the balls gripped between said discs and directed toward said receptacle.

2. A golf ball retrieving machine comprising a frame adapted to be moved over the ground, a shaft mounted transversely on said frame, a plurality of pairs of ball pick-up wheels mounted on said shaft at laterally-spaced locations thereacross, each wheel having a hub mounted in an axially-fixed location on said shaft, a resilient member mounted on said hub, and a centrally-apertured peripheral disc tiltably mounted on said resilient member in radially-spaced encircling relationship to said hub, the hubs of each said pair of wheels being mounted on said shaft at intervals normally spacing the peripheries of said

discs apart from one another by a distance slightly less than the diameter of the smallest ball to be picked up, said resilient member normally urging said disc into a plane perpendicular to said shaft, a ball receptacle mounted on said frame, and a ball ejector disposed in the path of the balls gripped between said discs and directed toward said receptacle.

3. A golf ball retrieving machine comprising a frame adapted to be moved over the ground, a shaft mounted transversely on said frame, a plurality of pairs of ball pick-up wheels mounted on said shaft at laterally-spaced locations thereacross, each wheel having a hub mounted in an axially-fixed location on said shaft, an annular resilient member mounted on said hub, and a centrally-apertured peripheral disc tiltably mounted on said resilient member in radially-spaced encircling relationship to said hub, the hubs of each said pair of wheels being mounted on said shaft at intervals normally spacing the peripheries of said discs apart from one another by a distance slightly less than the diameter of the smallest ball to be picked up, said resilient member normally urging said disc into a plane perpendicular to said shaft, a ball receptacle mounted on said frame, and a ball ejector disposed in the path of the balls gripped between said discs and directed toward said receptacle.
